CLAIM

The ornamental design for cap for automatic injector, as shown and described.

DESCRIPTION

FIG. 1 is a right side elevational view of a cap for automatic injector, showing our new design, the left side elevational view being a mirror image thereof;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a perspective view thereof.

Fig. 1.Fig. 2. Fig. 3.Fig. 6.Fig. 4.Fig. 5.
